LOCKER CABINET

Walter R. Radossevich, Calumet Park, Ill., assignor to
Superior Wire & Iron Products, Inc., Chicago, Ill., a
corporation of Illinois

Filed Sept. 21, 1964, Ser. No. 81,803

Term of patent 14 years

(Cl. D33—19)

FIG. A.FIGURE 1 is a front elevational view of a locker cabinet, showing my design;

FIGURE 2 is a side elevational view;

FIGURE 3 is a top plan view thereof, and

FIGURE 4 is an enlarged view of a door of the locker cabinet.

The back of the locker cabinet is of conventional construction and the side not shown is the same as the side shown in FIGURE 2.

I claim:

The ornamental design for a locker cabinet, substantially as shown and described.
